UNITED STATES PATENT OFFICE

164,335

TEXTILE FABRIC

Henry E. Stehli, Locust Valley, N. Y., assignor to Stehli & Co. Inc., New York, N. Y., a corporation of New York

Application February 15, 1951, Serial No. 14,215

Term of patent 3½ years

(Cl. D92—1)

To all whom it may concern:

Be it known that I, Henry E. Stehli, a citizen of the United States, residing in the town of Locust Valley, in the county of Nassau and State of New York, have invented a new, original, and ornamental Design for a Textile Fabric, of which the following is a specification, reference being had to the accompanying drawing, forming part thereof.

The figure is a face view of a textile fabric, showing my new design. The design unit is shown by interrupted lines and is repeated as indicated.

I claim:

The ornamental design for a textile fabric, substantially as shown and described.

HENRY E. STEHLI.
